WILLIAM H. HOGAN, OF MILWAUKEE, WISCONSIN.

DEVICE FOR DELIVERING REGISTER SLIPS.

Application filed February 18, 1927. Serial No. 169,236.

This invention relates to improvements in devices for delivering register slips.

On fast non-stop passenger and freight trains it is often necessary for the train men to deliver messages of importance to agents, operators, or dispatchers along the route. This is now accomplished by the train man wrapping a register slip or message around a stone, piece of coal, iron bolt, piece of wood or other convenient heavy object, any of which would cause injury to a person should he be struck by the same. Consequently when a message is thrown from a train in this manner the person to receive the message, afraid of being struck, will stand quite clear of the train and in a protected place, and often, especially at night, he can not find the thrown missile after the train has passed. If the message is not secured to a heavy object and is thrown loose, it flutters along with the draught of the train and is usually lost.

It is, therefore, the primary object of the present invention to overcome the above objections by providing a simple device for the delivery of registry slips which may be used with safety and effectiveness.

A further object of the invention is to provide a delivery device of the class described which is flexible and when thrown from a train it will hit dead and remain at the point thrown without bounding or rolling away.

A further object of the invention is to provide a delivery device of the class described which is indestructible, and which may be rolled or bent into a convenient space saving shape by operators for redistribution from time to time.

A further object of the invention is to provide a delivery device of the class described arranged to securely grip a message or register slip so that the same can not become inadvertently detached therefrom and which may also be painted any suitable bright color for ready visibility.

A further object of the invention is to provide a device for delivering register slips which is of very simple construction, is strong and durable, is inexpensive to manufacture, and is well adapted for the purposes described.

With the above and other objects in view the invention consists of the improved de-

vice for the delivery of register slips and its parts and combinations as set forth in the claim and all equivalents thereof.

In the accompanying drawing in which the same reference characters indicate the same parts in all of the views:

Fig. 1 is a side view of the improved delivery device showing the position it is held in when thrown from a train;

Fig. 2 is a view on a smaller scale showing the shape into which the device will bend or flex after hitting the ground;

Fig. 3 is a view on a smaller scale showing the shape into which the device may be bent and secured for storage and shipment;

Fig. 4 is a view of a form slip such as is intended shall be used with the device; and

Fig. 5 is a cross-sectional view taken on line 5—5 of Fig. 1.

Referring now more particularly to Fig. 1 of the drawing it will be seen that the device is normally of elongated form, preferably being about fourteen inches from end to end, and is formed of a heavy, covered copper wire of a suitable gauge.

The wire 8 forming the center or core of the device extends from end to end while the covering 9 is removed from each end of the wire, as at 10 and 11.

One end portion of the device is curved or hooked as at 12 while the uncovered portion of the wire at that end is formed in a loop 13.

The uncovered portion of the opposite end of the wire is bent with a straight off-set portion 14 and is then looped around, as at 15, and extended back inwardly, the extended portion having an off-set portion 16 adjacent the other off-set portion 14, and terminating in a loop 17. The shape of the bent and uncovered portion of the wire just described forms a clip having two pairs of engaging surfaces. Said clip is adapted to have inserted thereinto a folded form slip or message 18 and the same is securely held against undesired removal by the two pairs of engaging surfaces, as shown in Fig. 1.

It is intended that a number of the delivery devices be put into each engine cab. The form 18, such as is shown in detail in Fig. 4, is furnished with each delivery device placed in the engine cab. Each form slip has printed thereon indicia to cover any contingency and adjacent each line of in-

5 dicia 19 a circle 20 is printed. Now, if the engineer desires to make a report when passing the next agent or dispatcher he will punch a hole in the circle adjacent the pertinent indicia line on a slip, which has been signed before starting the run, and fold the slip and insert it into the clip portion of the 10 delivery device. Then, when the train is passing the desired point, the delivery device will be thrown straight downwardly from the train in the manner shown in Fig. 1. On striking the ground, the device will bend or flex somewhat, as shown in Fig. 2, and will therefore land dead. Due to its 15 visible color and the fact that it lands dead, the agent will readily locate the delivery device after the train has passed. From time to time the agents may bend and fasten the ends of each device together, as shown in

Fig. 3, and send the same to headquarters 20 for redistribution to trains.

From the foregoing description, it will be seen that the improved delivery device for register slips is of very simple and novel construction, and is well adapted for the 25 purposes set forth.

What I claim as my invention is:

A register slip delivery device, consisting of a readily bendable wire member, one end portion of the same being bent longitudinally adjacent its major portion with a pair of inwardly off-set portions to form a double gripping clip and the other end portion of said wire member being curved to form a 30 contact end. 35

In testimony whereof, I affix my signature.

WILLIAM H. HOGAN.
